UNITED STATES PATENT OFFICE.

MAX SCHEUER, OF NEW YORK, N. Y.

DESIGN FOR A HAND BAG.

Application filed August 12, 1922. Serial No. 3,361. Term of patent 7 years.

To all whom it may concern:

Be it known that I, MAX SCHEUER, a citizen of the United States, and a resident of the city of New York, borough of Manhattan, in the county and State of New York, have invented a new, original, and ornamental Design for Hand Bags, of which the following is a specification, reference being had to the accompanying drawings, in which—

Fig. 2 is a side view thereof.

I claim:

The ornamental design for a hand bag, as shown.

MAX SCHEUER.
